SAMUEL J. HOGGSON, OF NEW HAVEN, CONNECTICUT.

Design No. 4,142, dated June 7, 1870.

DESIGN FOR A HAND-STAMP.

The Schedule referred to in these Letters Patent and making part of the same.

To all whom it may concern:

Be it known that I, SAMUEL J. HOGGSON, of New Haven, in the county of New Haven and State of Connecticut, have invented a new Design for Hand-Stamp; and I do hereby declare the following, when taken in connection with the accompanying drawings and the letters of reference marked thereon, to be a full, clear, and exact description of the same, and which said drawings constitute part of this specification, and represent in—

Figure 1, a front view, and in

Figure 2, a side view.

This invention relates to a design for hand-stamp such as are used for marking linen, and for similar pur-

poses, and consists in the peculiar form of the base of the stamp, as more fully hereafter described.

The front and rear of the stamp are formed into legs A A, extending up to a base, B, and the space between the legs of semicircular form, and the outside contracted toward the base, as fully shown in the accompanying drawings. The stamp is fixed to the base B.

I claim as my invention—

The base for a hand-stamp, of the shape or form substantially as herein described.

Witnesses:

S. J. HOGGSON.

JOHN H. SHUMWAY,

A. J. TIBBITS.
